AMUSEMENT OR EXERCISING DEVICE

Wilson Pratt, Salt Lake City, Utah; David Wilson
Pratt, administrator of said Wilson Pratt, deceased

Application January 31, 1946, Serial No. 644,538

6 Claims. (Cl. 155—56)

1

This invention relates to improvements in hobby horses or the like, and more particularly to a novel device designed to be used for exercise or pleasure and which simulates the action of a running horse.

One of the objects of the invention is to provide a device of this character in which the simulation of the action of a running horse may be created by the rider who shifts his weight forward and backward from stirrup to saddle and vice versa.

Another object is to provide a device of this type which is of simple, inexpensive construction and including adjustable means to enable the device to be adjusted to accommodate riders of various weights.

With the foregoing objects outlined and with other objects in view which appear as the description proceeds, the invention consists in the novel features hereinafter described in detail, illustrated in the accompanying drawings and more particularly pointed out in the appended claims:

In the drawings—

Fig. 1 is a side elevation of an example of the device.

Fig. 2 is a rear elevation of the same.

Referring to the drawings, it will be noted that the device consists of three essential parts, a base 3, a seat 4 and connecting means 5 for supporting the seat above the base.

The base may be made in any suitable way. For example, it may consist of a pair of angle irons 6, arranged side-by-side and spaced from one another by blocks 7. Bolts 8 extend through the angle irons and blocks, to rigidly hold these parts together. Cross arms 9, rigid with the ends of the angle irons and extending outwardly therefrom, may be employed for lateral stability.

Each angle iron is provided intermediate its ends with an upstanding bracket 10, and each bracket is pivotally connected to the lower end of one of the front links 11 and one of the rear links 12. The front links are preferably of angle iron construction and they are rigidly and adjustably connected to a vertical triangular plate or member 13, by means of a bolt 14 or the like, which extends through an arcuate slot 15 in the plate. Due to this construction, the plate can be set at various angles relatively to the front links 11. As will be seen from Figure 1, the plate 13 is rockably mounted on a transverse pivot 30 extending between the spaced upstanding brackets 10. A coil spring or elastic means 16 has its front end pivotally connected to the rear end of the plate 13, and its opposite end pivotally secured to a threaded bolt 17, passing through a bracket 18, at the rear end of the base, and provided with a nut 19. As the nut bears against the

bracket, it will be obvious that turning of the nut will cause tensioning of the spring.

The figure 20 of a horse or the like is provided internally with a pair of vertical plates 21 that are rigidly secured at 22 to the body of the horse. The pair of front links 11, together form a main standard and are preferably provided at their upper ends with a common transverse bearing sleeve 23a which may be welded or otherwise secured to the links and cooperate with a pivot pin 23 to pivotally connect the standard to the plates 21. The rear links 12 which as before stated are pivoted at their lower ends to the brackets 10, are similarly connected at their upper ends, to 15 the respective plates 21 by pivots 24 and, together form a stabilizer which in cooperation with the main standard maintain the horse in a substantially horizontal position.

A second triangular plate 25 is rigidly connected to the upper ends of the links 11 by rivets or the like, as indicated at 26. A stirrup member 27 has an upper medial portion pivotally connected to the plate 25, as indicated at 28, and the end portions of the stirrup member forms treadles 29 projecting from opposite sides of the horse's body.

In operation, if the rider elects to go forward, he puts his weight on the treadles 29 and thus moves himself downward and forward. After

30 going as far forward as desired, he sits back in the saddle or seat 4, releasing his weight from the stirrups and since the links 11 would be working on a shorter fulcrum arm, the spring 16 returns him to his original position, and he continues on backward, due to momentum and the fact that the links 11 have a fulcrum arm acting to make the horse go backward. The tension of spring 16 is such that it just about balances the rider in the position as shown in Fig. 1.

40 When the horse proceeds backward, the treadles 29 will abut against the links 11 and thus advise the rider of the rearward limit of the horse's motion. When the desired backward movement has been reached, the rider in order to go for-

45 ward, leans forward, putting his weight against the stirrups, which makes the fulcrum arm less than if sitting on the horse, and, therefore, he moves forward and upward through an arc. In other words, the rider, by shifting his weight from the stirrups to the saddle and vice versa, creates an unbalanced condition which causes movement of the supporting means 5 about the pivot point or center 30.

As the coil spring has its front end pivotally 55 connected to the rear end of the plate 13 and its rear end pivotally secured to the bolt 17, the adjustment of the plate relative to the links 11 is of paramount importance, as far as the ease of operation is concerned. A slight change of angle 60 between the triangular adjustable plate and the

upright supporting members 11 makes the device either difficult or easy to operate. The included angle between the links 11 and the line of tension afforded by the spring may vary between 90 degrees and 45 degrees.

It will be understood that as the horse moves forward or backward, it will remain in a horizontal position, and the construction is such that the device may be used for amusement purposes or as an exerciser.

While I have disclosed the invention in connection with a hobby horse, it is obvious that the body 20 may be made to simulate other animals, birds, etc., or the seat 4 could be simply a chair.

From the foregoing, it is believed that the construction, operation and advantages of the device may be readily understood, and while I have disclosed what I now consider to be a preferred embodiment of the conception, I am aware changes may be made in the details disclosed without departing from the spirit of the invention, as expressed in the following claims.

What I claim and desire to secure by Letters Patent is:

1. In a device of the character described, a base, a standard fulcrumed on said base, a seat member pivotally mounted at the upper end of said standard, a stabilizer means for said seat, a pedal mechanism fixed to said standard adjacent said seat and disposed forwardly out of vertical alignment with the fulcrum of said standard, a spring anchor bracket fixed to the fulcrumed end of said standard, and double acting spring means extending between said bracket and said base, normally urging said standard to a neutral balanced position from either direction, whereby a downward pressure on said pedal mechanism will offset the opposed tension of said spring and tend to throw said standard off balance, causing the seat member and standard to rock forwardly on its fulcrum, while a shifting of pressure from said pedal to said seat member will relieve said spring tension and cause a reverse movement of said seat member and standard.

2. In a device of the character described, a base, a main standard and a stabilizing standard fulcrumed at their lower ends on said base, at longitudinally spaced points, a seat member pivotally mounted at the upper end of said standards, said main standard having angularly disposed brackets fixed thereon adjacent its upper and lower ends, said brackets extending longitudinally of said base and projecting respectively in opposite directions to points out of vertical alignment with the fulcrum of said main standard, spring means connected between the projecting end of said lower bracket and a fixed point on said base, its normal line of pull urging said main standard and seat member to a neutral balanced position on said fulcrum, said lower bracket, upon the rocking of said standard, being arcuately movable in opposite directions to shift the line of pull of said spring, alternately above and below said normal balanced line of pull, and a pedal member pivotally suspended from the projecting end of said upper bracket, whereby a downward pressure on said pedal will offset the opposed tension of said spring and tend to throw said standard off balance, causing the seat member and standard to rock forwardly on its fulcrum, while a shifting of said pressure from said pedal to said seat member will relieve said spring tension and cause a reverse movement of said seat member and said standard.

3. In a device of the character described, a base, a seat member, a main standard and a supplemental standard spaced from the main standard and fulcrumed on said base and pivotally connected to said seat and supporting the latter for longitudinal rocking movement on the base, a double-acting spring anchor bracket fixed to said main standard adjacent its lower end and projecting rearwardly beyond the fulcrum point of said main standard, spring means extending between the projecting end of said spring anchor bracket and a fixed point on said base, normally urging said main standard to a neutral balanced position on its fulcrum, a pedal bracket fixed to the upper end of said main standard and projecting forwardly out of vertical alignment with the fulcrum point of said main standard, and a pedal pivotally suspended from said pedal bracket and disposed forwardly of said main standard, whereby a downward pressure on said pedal will offset the normal tension of said spring and tend to throw said main standard off balance, causing said seat member and standards to rock forwardly on their fulcrums, while an alternate shifting of pressure from said pedal to said seat member will relieve the forward tension on said spring and cause a reverse movement of said seat member and standards.

4. In a device of the character described, a base, a vertically disposed longitudinally extending anchor bracket fulcrumed on said base, a standard fixed at its lower end to said bracket and pivotally secured at its upper end to a seat member, means for stabilizing said seat member, said anchor bracket projecting longitudinally in one direction a predetermined distance beyond its fulcrum, spring means connected between the projecting end of said anchor bracket and a fixed point on said base, a pedal bracket fixed to the upper end of said standard and projecting longitudinally of said frame in the opposite direction, and a pedal pivotally suspended from said pedal bracket, whereby a downward pressure on said pedal will offset the normal tension of said spring and tend to throw said standard off balance, causing said seat member and standard to rock longitudinally in one direction on said fulcrum, while an alternate shifting of pressure from said pedal to said seat member will relieve the tension on said spring and cause a reverse rocking movement of said seat member and standard.

5. Apparatus as claimed in claim 2, including means to adjust the position of said lower bracket with respect to said main standard to vary the line of tension of said spring with respect to the fulcrum of said main standard.

6. Apparatus as claimed in claim 4, wherein said anchor bracket and standard are relatively adjustable to permit variation of the line of tension of said spring with respect to the fulcrum of said anchor bracket.
